UNITED STATES PATENT OFFICE.

GILBERT LAFAYETTE LOPER, OF NORCATUR, KANSAS.

ROTARY ENGINE.

No. 807,297.

Specification of Letters Patent.

Patented Dec. 12, 1905.

Application filed January 20, 1905. Serial No. 241,955.

To all whom it may concern:

Be it known that I, GILBERT LAFAYETTE LOPER, a citizen of the United States, residing at Norcatur, in the county of Decatur and State of Kansas, have invented a new and useful Improvement in Rotary Engines, of which the following is a specification.

My invention relates to rotary engines of that class in which the outside casing revolves and the steam is admitted to the same through a central core having steam-ports.

The invention consists in the novel construction and arrangement of parts acting upon this general principle, which I will now proceed to describe with reference to the drawings, in which—

Figure 1 is a vertical section through the engine, taken longitudinally to the shaft. Fig. 1^a is a detail of a modification. Fig. 2 is a horizontal section. Fig. 3 is a vertical transverse section on line 3 3 of Fig. 1 looking in the direction of the arrow. Fig. 4 is a perspective view of the hub and sliding abutment with the revolving casing in section. Fig. 5 is a perspective view of the stationary hub; Fig. 5^a, a perspective view of the sliding abutment, which fits and slides in the diametrical slideway in the hub. Figs. 6 and 6^a are inside face views of the two parts of the hub, showing how the inlet and exhaust ports are formed; and Fig. 7 is an inside view of the casing.

In the drawings, 12 represents the main shaft, which is rigidly connected by a key 23 to the outside cylindrical casing 11, which revolves with the shaft. This shaft is journaled at one end in an outside pillow-block 15, and at the other end is journaled in a bearing 3 in a casing forming a combined steam-chest and shaft-support 4. If desired, the shaft may extend entirely through the steam-chest and be provided with a stuffing-box on the outside, as seen in Fig. 1^a. The upper portion of this casing is hollowed out to form the steam-chest 2, and the top of this steam-chest is closed by a detachable cover 1, bolted or screwed to the steam-chest, and having a central opening through which steam is admitted from a pipe coming from the governor. The middle part 5 of the steam-chest and shaft-support is projected laterally in the form of a hub 4^a, whose neck portion 4^b is smaller than its outer periphery and whose outer circular periphery lies inside the outer casing a little distance 55 from the inside wall of the same. A de-

tachable collar 13, made in two pieces, is screwed to the inner side of the casing and incloses the larger peripheral portion of the hub. In this hub portion, which is stationary, are formed two opposite steam-ports 7 7, which open in diametrical position on the periphery of the hub into the space between the hub and casing. At the point where these inlet-ports open into the steam-chest are arranged the inlet-valves 6 6, one for each port and 65 opening inwardly to the steam-chest. These valves are opened successively by a cam-flange 5 on the main shaft, which flange as the shaft revolves catches under the free end of the valve and lifts it away from its seat, allowing steam to pass from the steam-chest to the annular space within the casing outside the hub, as seen in Fig. 4. These valves are hinged at their outer edges and are free at their inner edges next to the cam-flange, and, 70 if desired, may have springs 8 to cause them to seat more positively; but usually the steam-pressure will be sufficient for this. In the central hub and half-way between the steam-inlet ports are two exhaust-ports 18 18. 80 These ports open through the neck of the hub on opposite sides of the engine and by means of a yoke-pipe 25 communicate with a common exhaust-pipe 26, which discharges into the air or into a condenser. These exhaust-ports 85 communicate with the annular steam-space between the hub and the case in a peculiar way, which I will now describe. The large part of the hub is made in two or more parts joined together in a plane at right 90 angles to the shaft and fastened together by screws. In each adjacent face of the two parts of the hub are formed part of the steam-inlet ports 7 and part of the steam-exhaust ports 18, as seen in Figs. 1, 6, and 6^a. Diametrically across the outer face of the hub is formed a slideway *w*, in which slides back and forth a movable abutment 8. This abutment has a longitudinal slot 8^a where it incloses the main shaft. The middle part of this groove 100 and the middle part of this sliding abutment are made comparatively shallow, while the ends of the slideway in the hub and the ends of the sliding abutment are made the full thickness of the annular steam-space between the 105 hub and the casing. These thickened ends, when moved outwardly to contact with the inner wall of the casing, (see Fig. 4,) form the stationary back thrust abutment against which the steam presses. The front abut- 110

ment, or movable piston, which receives the moving pressure of the steam, is constructed as an inward projection 17 from the casing, extending to contact with the circular periphery of the stationary hub 4^a. The expanding steam-chamber is formed between the inner periphery of the case, the outer periphery of the hub, the piston projection 17 on the case, and the end of the abutment when 10 extended, and steam is admitted to this space and exhausted from it every half-revolution. The manner of admitting the steam has already been described as passing in through the port 7, opening on the periphery just in 15 front of each end of the movable abutment. The exhaust-ports do not open on the periphery of the hub, but open into the wide slot of the hub inside the periphery of the hub, so that when the sliding abutment is projected 20 at one end to imprison the steam and cause it to exercise its working power on the piston of the case at the same time the other end of the sliding abutment retires into the broad slot of the hub and uncovers the exhaust-port, 25 as in Fig. 4, so that the steam behind the piston can escape. To permit this to occur, the ends of the sliding abutment are made wedge-shaped, so that when they retire into the hub they allow the exhaust-ports 18 to become 30 alternately uncovered.

From what has been said it will be understood that the sliding abutment must at every half-revolution of the casing change its position, so as to cut off the active exhaust-port 35 and bring into action the other inlet-port and the other exhaust-port. This is effected by a cam-groove 14, Fig. 7, formed in the outer head of the casing, which cam-groove receives a laterally-projecting roller 8^b on the sliding 40 abutment and gives it at the right time its proper reciprocating action to allow the piston 17 to pass one end of the abutment and project the other end to contact with the inner periphery of the case.

45 To make steam-tight joints between the moving parts, steam-packing-ring sections 19 are arranged between the sides of the hub and the heads of the casing. Steam-packing pieces 20 are arranged between the sides of the ends of 50 the movable abutment and the casing-heads. A steam-packing 21 is arranged along the edge of the movable abutment where it contacts with the outer case, and a steam-packing 22 is arranged on the inner edge of the piston 55 projection 17 of the case where it rubs against the central hub.

Having thus described my invention, what I claim as new, and desire to secure by Letters Patent, is—

60 1. A rotary engine comprising a rotating case having inwardly-projecting piston, a stationary hub with inlet and exhaust ports, a combined steam-chest and shaft-support, a valve arranged in the steam-chest and controlling the inlet-port and a shaft fixed to the ro-

tating case and bearing a cam-flange in the steam-chest arranged to act upon and open the inlet-valve substantially as described.

2. A rotary engine comprising a rotating case with inwardly-projecting piston and detachable collar, a stationary hub with inlet and exhaust ports, a combined steam-chest and shaft-support, a valve arranged in the steam-chest and controlling the inlet-port, a rotating shaft with cam-flange in the steam-chest 70 for operating the inlet-valve, the hub being formed with exhaust-ports opening on the neck of the hub between the casing and the steam-chest substantially as described. 75

3. A rotary engine comprising a rotating case having an inward projection forming a piston, a stationary hub arranged within the case and having inlet and exhaust ports formed therein and a diametrical groove, and a diametrically sliding abutment arranged in said 80 groove, and means for sliding the abutment substantially as described.

4. A rotary engine comprising a rotating case having an inwardly-projecting piston, a stationary hub made smaller than the case to 90 leave an annular steam-space and having a diametrical slideway, a diametrically sliding abutment arranged in the slideway and means for shifting this abutment, the stationary hub being formed with inlet-port opening on the 95 periphery and with an outlet-port opening into the slideway of the hub in which the abutment moves substantially as described.

5. A rotary engine comprising a rotating case having an inwardly-projecting piston, a 100 stationary hub having a diametrical slideway, an abutment sliding therein and made with wedge-shape ends and means for shifting the abutment, the stationary hub being formed with inlet-port opening on the periphery and 105 outlet-port opening into the slideway and arranged to be exposed by the wedge-shape end of the abutment as described.

6. A rotary engine, comprising a rotating case having an inwardly-projecting piston and 110 a cam-groove in its head, a stationary hub with inlet and outlet ports and a sliding abutment having a friction-roller playing in the cam-groove of the head of the case substantially as described. 115

7. A rotary engine comprising a rotating case and attached shaft, the case having an inwardly-projecting piston, a stationary hub made in two sections joined together in a plane at right angles to the shaft and formed with inlet and exhaust ports partly in each half of the hub, and a diametrically-arranged and sliding abutment substantially as described. 120

8. A rotary engine, comprising a rotating case with attached shaft, the case having an inwardly-projecting piston, a stationary hub having a diametrical slideway shallow in the middle and opening on one side of the hub and extending across the full steam-space of 125 130

the hub at the ends and a sliding abutment made of corresponding shallow proportions at the middle and wide at the ends substantially as described.

5 9. A rotary steam-engine comprising a rotating case with inwardly-projecting piston, a stationary hub with diametrically-arranged sliding abutment, said hub being formed with its exhaust-opening in the slideway of the 10 abutment to be uncovered by the reciprocation of the latter substantially as described.

10. A rotary engine comprising a combined steam-chest and shaft-support having a laterally-projecting and enlarged hub with inlet 15 and exhaust ports in it, valves arranged in the

steam-chest controlling the inlet-ports, a rotating case with inwardly-projecting piston, a shaft-rigidly attached to the case and extending into the steam-chest and bearing a cam-flange acting upon the inlet-valve, a detachable 20 ring or collar secured to the case about the neck of the hub, a diametrically-disposed sliding abutment arranged in a slideway of the hub and means for shifting it substantially as described.
